UNITED STATES PATENT OFFICE

WALTER DOLL, OF GRANVILLE, NEW YORK

GAME APPARATUS

Application filed September 29, 1927. Serial No. 222,772.

This invention relates to improvements in game apparatus and refers more particularly to such apparatus as can be used in playing or practicing the well known game of 5 "golf", in such limited space as to avoid the necessity of chasing golf balls.

An important object of the invention, in its broader aspects, is to provide a compact apparatus wherein a captive ball member is 10 supported in position to be struck by a golf club or the like, and wherein means are provided for indicating the nature of blows struck upon the ball member.

Another object is to provide such a device 15 with means for indicating the angularity, in two planes, of blows struck against the captive ball member.

Another object is to provide such a device 20 with novel mechanism for transmitting driving impacts from the ball member to the indicating means with reduced force.

Another object is to provide such a device 25 with a novel friction brake whereby to impose a drag on certain parts and thus to restrict movement of such parts to reasonable limits.

Another object is to provide such a device 30 with means for supporting the captive ball member in different selective positions to permit the proper use of different clubs.

Another object is to provide such a device 35 with means whereby it can be quickly and easily reset to playing position after its mechanism has been actuated.

Another object is to provide such a device 40 which will be simple in construction, strong and durable in service, economical in manufacture, and a substantial advance in the art, and which constitutes apparatus which is well adapted for instruction, recreation and exercise.

With the foregoing and other objects in view, the invention resides in the novel construction, combination and arrangement of 45 parts hereinafter set forth, shown in the accompanying drawings illustrating one embodiment of the invention, and pointed out in the appended claims.

In the drawings, Figure 1 is a top plan 50 view of the device;

Fig. 2 is a vertical longitudinal sectional view on the line 2-2, Fig. 1, through the casing and showing the internal mechanism in elevation;

Fig. 3 is a fragmentary top plan view of 55 the internal mechanism of the device on a larger scale;

Fig. 4 is a vertical longitudinal sectional view on line 4-4 of Fig. 3 showing parts 60 of the casing; and

Fig. 5 is a detail sectional view of the 65 brake, taken on line 5-5 of Fig. 3.

In carrying out the invention, the improved mechanism may preferably be mounted in a casing which has been shown conventionally in the drawings as of rectangular outline and comprising a bottom 10, side walls 11, 11, end walls 12, 12, and a fabricated top which will be described more in detail hereinafter. Such casing constitutes a supporting frame for the mechanism and may preferably be set in the ground outdoors or in a recess in the floor of a room, or otherwise disposed with its top substantially flush with the feet of a player using the device. The internal mechanism of the apparatus may preferably be mounted as a 70 unit within the casing and the arrangement such that the entire apparatus may be readily portable, if desired.

A mounting flange 14 is secured as by screws 75 15 to the bottom 10 of the casing and constitutes a support for a swivel post 16 which extends upwardly within said casing. A swivel supporting sleeve 17 is rotatably mounted upon the swivel post 16 and held in place thereon by means of a suitable collar 18 secured by set-screws 19 or the like, and said swivel sleeve constitutes the support or central supporting member of a swiveled frame, portions of which are adapted for swinging 80 movement in two perpendicular planes. At its opposite sides the sleeve 17 is provided with bosses 20 having threaded openings 21 which are in alignment with each other and which are adapted to receive the screw-threaded extremities of a pair of pivot-screws 22, which serve to pivotally connect a frame or beam 23 to the sleeve 17 in such a manner

95 that its free ends swing upwardly and downwardly in a vertical plane. Said beam 23 100

comprises a yoke 24 adapted to encircle the sleeve 17 and its bosses 20, and is provided with bearing members 25 at its opposite sides for the reception of the pivot screws 22.

5 A rearwardly disposed extension 26 of said yoke 24 carries a pair of transversely apertured lugs or bosses 27 which are apertured for the reception of a pin 28, and pivotally mounted upon said pin and between the 10 spaced bosses 27 is an arm 29 provided at its free end with a hammer head 30, as best shown in Fig. 4. The forward end or face of said hammer head 30 may preferably be slightly curved and if desired may be hardened 15 and capable of withstanding and transmitting sharp blows, as will hereinafter be explained, and the rearward end of said hammer head carries a captive ball member 31 which may be suitably formed and constructed to have substantially the same physical characteristics and properties as an ordinary golf ball. In Figs. 2 and 4 the captive ball member 31 has been shown in its normal position of rest ready to be struck by a golf 20 club or the like and it will be noticed that in such normal position said ball member is disposed immediately above the preferably fabricated top of the casing; and the arm 29 extends through an opening 32 in the top 25 board 33, said top board being set slightly below the upper edges of the side walls 11 and end walls 12, and being covered by a suitable yielding material, such as a piece of coco-matting 34 or the like. The coco-matting is 30 also provided with an opening 35 through which the arm 29 and hammer-head 30 are adapted to operate, said opening being shown as of segmental shape, with its arcuate edges struck from the center of the swivel post 16. 35 The coco-matting 34 makes possible the use of the device without jeopardizing the heads of the golf clubs which are used in striking the captive ball-member 31. A flat spring 36 is also carried by the extension member 40, it having one of its ends anchored on a cross-bar 37 and its other end free and provided with a substantially V-shaped catch 38 which is adapted to engage in a correspondingly shaped notch 39 in the arm 29 in such 45 a manner as to retain said arm 29 in its upwardly extended position, but without offering enough resistance to affect the stroke of the golf club on the ball-member 31.

Also carried by the rearward extension 26 50 is a socket-member 40 within which is operable a spring-pressed plunger 41 which is held in place by a detachable cover plate 42 and provided with a collar portion 43 against the lower side of which a compression spring 44 is adapted to bear. One end of the plunger 41 extends upwardly through the cover plate 42 and in such a position as to be capable of being struck by the hammer-head 30 as it swings downwardly about the pin 28, and the 55 lower end of said plunger 41 extends slightly

below the socket-member 40 and bears against a rearwardly extending arm 45 of a rocker 46 which is pivoted at 47 to the frame extension 26. The rocker 46 is further provided with a forwardly extending arm 48 which normally bears against one face of a horizontal arm 49 of a bell-crank 50 which is pivoted at 51 to the yoke 24 preferably at a point forward of the swivel sleeve 17. A second arm 52 of the bell-crank 50 extends upwardly in front of the swivel sleeve 17 and has its upper extremity bifurcated as at 53 in such a manner as to be capable of straddling a guide-member 54.

80 The guide-member 54 may preferably be in the nature of a small rod or taut wire which is supported in a horizontal position and radially with reference to the axis of the swivel post 16. The rod or wire has its rear end secured in any suitable manner to an anchoring post 55 on the sleeve 17, and has its forward end connected to a stud 56 which extends upwardly from the forward end of a supporting bar 57 carried by the sleeve 17. The bar 57 and guide-member 54 are relatively long as compared with the diameter of the swivel post 16 and constitute a pointer for indicating the angularity of blows struck upon the ball-member 31 in one plane. For this purpose the casing of the apparatus is provided with a horizontal dial plate 58 which overlies the bar 57 and has an arcuate slot 59 through which the stud 56 extends upwardly in such a manner as to dispose the guide-member 54 above said dial plate. The center of curvature of the arcuate slot 59 is coincident with the axis of the swivel post 16, so that said bar 57 and guide 54 and associated parts are enabled to swing in a horizontal plane, and to opposite sides of the longitudinal center of the casing or dial plate. Adjacent the inner edge of the slot 59 is a series of radial graduations 59a which indicate angular movement of the guide-member from the central position of rest. Such graduations may be arranged and designated as desired. Dial plate 58 is also provided with a series of spaced arcuate lines 60, 61, 62, 63 and 64 which are also concentric with the slot 59 and so related to each other as to indicate distance values. There are five such arcuate lines shown in Fig. 1, respectively marked to indicate 100 yards, 150 yards, 200 yards, 250 yards and 300 yards, but it is obvious that either a greater or smaller number of such arcuate indicating lines may be employed, if desired, and their valuation markings correspondingly or differently lettered.

110 An indicating member 65 in the form of an apertured sphere is freely slidable upon the guide-member 54 between the stud 56 and the bell-crank arm 52, and the arrangement is such that as movement is imparted to the bell-crank 50, it transmits such movement to the indicator member 65 and causes said in- 115 120 125 130

dicator to move longitudinally on the guide 54 a distance commensurate with the actuating force. In its normal position, of course, said indicating member must be disposed against the bifurcated impelling end 53 of the bell-crank arm 52 so that there will be no lost motion of said arm with reference to the indicating means. In order that the bell-crank arm 49 may always be maintained 10 in engagement with the rocker 46, a suitable spring 66 is employed, said spring being shown in the drawings as of the flat strip type, its free end being adapted to bear against a portion 67 of the yoke 24 in such 15 a way as to always be maintained under tension.

A cylindrical portion 68 extends forwardly from the yoke 24 and carries a rod 69, the forward extremity of which is bent upwardly 20 as at 70 and provided with a pointer 71 which is adapted to cooperate with a dial 72 to indicate the angularity of blows in the vertical plane. The dial 72 may be formed of sheet metal or the like, and is longitudinally curved 25 on an arc struck from the center of the swivel post 16 and preferably extends above the top edge of the casing walls 11 and 12 for the purpose of facilitating quick reading, and the rear surface of said plate or dial 72 is 30 characterized by a pair of parallel lines 73, 74, each of which indicates the normal position of the pointer 71 for selective supported positions of the captive ball member 31.

As is well known to those skilled in the art, 35 different golf clubs are used for different strokes, depending upon the position in which the ball lies, and such differences in play are taken into account and this machine makes possible its use with various types of golf clubs. For example, when the parts are in 40 position as shown in Fig. 2 with the extremity of the pointer 71 registering with the dial line 73, the ball 31 is set for an iron or brassie shot. By slightly tilting the beam 23 about the axis of the pivots 22, said ball member 31 can be raised up slightly, and when 45 such an adjustment is made so that the extremity of the pointer 71 registers with the dial line 74, the ball member is in position for 50 a tee shot. To insure the absolutely level setting of the mechanism, the cylindrical portion 68 of the beam carries a weight 75 which is adjustable longitudinally with reference to the beam and capable of being secured in adjusted position by a set-screw 76 or the like.

When the apparatus is first set, said weight 75 is adjusted to a position for balancing the beam 23 with the arm 29 in its downward position, as indicated by dotted lines in Fig. 60 4. Thereafter adjustment of the weight 75 may only be necessary occasionally in order to compensate for slight variations due to vibration or perhaps slight wear of some of the parts.

After the apparatus has been set, the frame

or beam which is balanced by the weight of the arm 29 and ball 31 thereon may be tilted about the axis of the pivot 22 as before stated. This is done by taking hold of the ball 31 and moving it vertically one way or the other to change its height, thus swinging the frame on its said pivots. The tension on brake band 84 holds the frame so that the ball will remain in position to which it is raised or lowered until it is struck by the club.

The blows delivered to the ball-member 31 are of considerable force, and it is desirable to transmit such blows to the indicating means with reduced force whereby to render said indicating means operable in a compact apparatus, and for this purpose a novel brake 77 is employed in connection with the beam 23. Said brake comprises a brake-drum 78 which is keyed, as at 79, or otherwise secured to one end of a shaft 80, said shaft being journaled for rotation in lugs 81 carried by the yoke extension 26. Also keyed to said shaft 80 preferably between the spaced lugs 81 is a pinion 82 which meshes with a gear-segment 83 carried by the swivel sleeve 17, said gear-segment having its axis coincident with the axes of the pivot-screws 22. Substantially encircling the brake drum 78 is a brake band 84 which has its extremities secured, as by the bolt 85 and adjusting nut 86, to a lateral bracket 87 of the yoke extension 26, and the arrangement is such that said brake-band 84 is constantly in frictional engagement with the periphery of the brake-drum 78. Thus the swinging movement of the beam 23 in a vertical plane results in partial rotation of the pinion 82 by virtue of its engagement with the segmental gear 83, and correspondingly causes relative rotation of the brake-drum 78 with reference to the anchored brake-band 84. Such rotation, however, is resisted by the frictional engagement of the brake-band against the brake-drum with the result that the swinging movement of the beam is considerably overcome. The frictional resistance offered by the brake can be varied or adjusted at will by the manipulation of the adjusting nut 86. This arrangement is particularly simple and effective, and is important in view of the substantial leverage or rather the distance between the pointer 71 and the horizontal center of rotation.

The use of the apparatus will no doubt be clear from the foregoing description, but brief recapitulation will be resorted to. After the device has been set in a perfectly level condition and is desired for use, the ball 31 is placed in its playing position above the coco-matting 34 and the indicating means are so disposed that the guide member 54 is directly over the longitudinal center of the dial plate 58, and the slideable indicator 65 is in engagement with the front side of the bell-crank arm 52. The player or user then stands beside the device with his feet level

with the top of the casing and, having selected a proper club, he strikes the captive ball 31 in exactly the same manner that he would strike a free golf ball on a regular golf course. The impact of the golf club against the ball 31 overcomes the resistance of the spring 36 and swings the arm 29 downwardly about the center of the pivot pin 28, causing the hammer-head 30 to forcibly strike 10 against the upper end of the plunger 41. This results in downward movement of said plunger 41, against the action of the compression spring 44, and such movement is communicated through the arms 45 and 48 15 of the rocker 46 to the bell-crank 50. The arm 52 of the bell-crank 50 is thus caused to swing forwardly with a quick movement, pushing the indicator 65 along the guide 54, and said indicator will come to rest at a position intermediate the ends of said guide 20 commensurate with the force which has been delivered to it. The approximate distance which a free golf ball would be driven by the same blow will be indicated by the position of rest of the member 65 relative to the graduations 60 to 64. If the blow of the golf club is absolutely true and without angular deviation in either plane, neither the swinging arm 57 nor the beam 23 will be 25 caused to appreciably move, but if the blow is not absolutely true, there will be movement of one or both of said members 57 and 23, and the extent of angular deviation in the vertical and horizontal planes will be indicated 30 by the apparatus. For example, if the ball is lofted, that is struck below its horizontal axis, the pointer 71 on beam 23 will be caused to swing downwardly in a vertical plane about the axis of the pivot screws 22, and will come to rest at a position spaced 35 away from the indicating lines 73 or 74, which ever was used to determine the neutral starting position. Similarly, if the ball is topped, that is struck above its horizontal center, said pointer 71 on beam 23 will swing upwardly an amount commensurate with the deviation of the blow. In a like manner the bar 57 will be caused to swing about the axis of the swivel post 16 in either one direction or the other dependent upon whether the ball is hooked or sliced, and in some instances there will be indication of angular deviation in both planes at once, and with 40 respect to both the vertical and horizontal axes of the ball member.

From the foregoing it will be evident that a very simple yet practical apparatus has been provided for golf players, whereby they 45 may practice with a view to improving their game very substantially without the necessity of chasing balls, or they may use the device for recreational or amusement purposes as will be obvious. The device is very simple in construction and strong and du-

rable in service, and one which constitutes a substantial advance in the art.

Obviously the invention is susceptible of numerous modifications in the details of construction and arrangement of parts and the right is herein reserved to make such changes as fall within the scope of the appended claims without departing from the spirit of the invention.

What I claim, is:

1. In apparatus of the class described, a swiveled frame, a captive member pivoted to said frame and adapted to be struck by a golf club or the like, the pivot extending substantially in the plane in which the frame may 75 swivel, a stationary plate having two series of indications, indicating means responsive to the pivotal movement of the captive member and cooperating with one of the series, and indicating means responsive to a 80 swiveling movement of the frame and cooperating with the other series, for separately indicating the force and angularity of a blow delivered to said captive member, both of said means extending in one direction away from the swivel and the captive member being located away from the swivel, in the opposite direction, and the first said indicating means including a movable indicator and devices 85 operable from the captive member and acting on the movable indicator, such devices being mounted on the frame in a position to be struck by the captive member.

2. In apparatus of the class described, a supporting frame, a swiveled frame thereon, a captive member pivoted to said swiveled frame and adapted to be struck by a golf club or the like, the pivot extending horizontally, a stationary dial, mounted on the supporting frame, and a pointer carried by the swiveled frame, and cooperating with the dial to indicate on the dial the angularity of a blow delivered to said captive member, the dial being located at one side of the swivel and the captive member at the other side.

3. In apparatus of the class described, a captive member, means for supporting the member in position to be struck by a golf club or the like, a substantially horizontal guide, a distance indicator slidable thereon, means for mounting the guide for a lateral movement when the captive member is struck, and means for transmitting percussive forces from said captive member to said distance indicator, whereby to move the indicator a distance commensurate with the force of the blow struck.

4. In apparatus of the class described, a swiveled frame, a captive ball member pivoted to said frame and adapted to be struck by a golf club or the like, a slidable distance indicator supported by said frame, means for transmitting percussive forces from the captive ball member to said distance indicator, whereby to move the indicator a dis-

tance commensurate with the force of the blow struck, and means for indicating the angularity of the blow with reference to the center of the ball member.

5. In apparatus of the class described, a swiveled frame, a captive ball member pivoted to said frame and adapted to be struck by a golf club or the like, dual, dial means, and movable indicator members for approximately indicating the distance and direction, respectively, which a free golf ball would have when a blow is delivered with reference to the horizontal and vertical axes of the ball member, and mechanism controlling the indicator members, and operable directly by the pivotal captive member for initiating such dual indication.

6. In apparatus of the class described, a swiveled frame, a captive ball member pivoted to said frame and adapted to be struck by a golf club or the like, two stationary dials, one of which includes dual indicating means, and indicator members, one of which is directly carried by the frame and another of which is carried by a separate indicator member swiveling with the frame and the indicator members cooperating respectively with said dials, and means operable by the captive ball member and acting on the other indicator, whereby the separate indicator and such other indicator are adapted to indicate direction and distance of a golf ball drive commensurate with the blow delivered to said captive ball member.

7. In apparatus of the class described, a captive ball member, a frame provided with means permitting its swinging movement in two planes perpendicular to each other, a ball carrying arm pivoted to said frame and movable relatively thereto, dial means provided with two series of indications, stroke indicating means carried by and movable with the frame whereby to indicate at one series of indications the angularity of blows struck upon the ball member, and means operable by the ball member whereby to indicate the force of the blows at the other series.

8. In apparatus of the class described, a captive ball member, a frame provided with means permitting its swinging movement in two planes perpendicular to each other, a ball carrying arm pivoted to said frame and movable relatively thereto, means for indicating the direction of blows struck upon the ball member when the frame moves in the two planes, and means including a stationary dial, a movable indicator member supported by the frame, and devices directly operable by the arm for causing the indicator member to cooperate with the dial, for indicating the distance which would be traversed by a free ball under the same blows.

9. In apparatus of the class described, a captive ball member, a pivoted arm carrying said ball member and adapted to support the

same in position to be struck by a golf club, distance indicating means comprising a substantially straight horizontally elongated guide and a slideable member mounted thereon, and means including a bell-crank lever for transmitting percussive forces from the ball member to said slideable member whereby to move the slideable member on the elongated member a distance commensurate with the blow struck.

10. In apparatus of the class described, the combination of a frame, a member mounted thereon in position to be struck by a club or the like, a substantially horizontal guide on the frame, an indicator slideable on the guide, and means including a combination of levers for acting on the indicator and movable by a blow given on said member whereby the levers move the indicator on the guide with reduced force.

11. In apparatus of the class described, a rotatable support, a beam pivoted to said support for swinging movement on an axis perpendicular to that of the support, a stationary dial a captive ball member pivoted to said beam, means carried by the beam for cooperating with said dial to indicate topped and lofted balls as a result of the blows delivered to said ball member, and means operatively connected between the beam and the support whereby to partially overcome the force of the delivered blows.

12. In apparatus of the class described, a rotatable support, a beam pivoted to said support for swinging movement on an axis perpendicular to that of the support, a stationary dial, a captive ball member pivoted to said beam, means carried by the beam for cooperating with said dial to indicate topped and lofted balls as a result of the blows delivered to said ball member, and frictional engaging means operatively connected between the beam and the support whereby to partially overcome the force of the delivered blows.

13. In apparatus of the class described, a rotatably supported sleeve, a beam pivoted to said sleeve for swinging movement on an axis perpendicular to that of the sleeve, a stationary dial, a captive ball member pivoted to said beam, means carried by the beam for cooperating with said dial to indicate topped and lofted balls as a result of the blows delivered to said ball member, cooperating gear members respectively carried by the sleeve and the beam, one of said gear members being caused to rotate by a swinging movement of the beam, a brake drum rotatable with said last-mentioned gear member and a brake band for frictionally engaging the brake drum to partially overcome the rotative effect.

14. In apparatus of the class described a swiveled frame, a captive ball member pivoted to said frame and adapted to be struck

5 by a golf club or the like, a stationary dial, a pointer carried by the frame and cooperating with the dial to indicate a topped or lofted ball as a result of the blow delivered to said ball member, and friction brake means for restricting the movement of said swiveled frame.

10 15. In apparatus of the class described, a swiveled frame, a captive member movably mounted on said frame and adapted to be struck by a golf club or the like, a movable distance indicator supported by said frame, leverage means for transmitting percussive forces from the captive member to said distance indicator, whereby to move the indicator a distance commensurate with the force of the blow struck, and means acted upon by the captive member and swiveled frame for indicating the angularity of the blow with 20 reference to the captive member.

16 16. In apparatus of the class described, a horizontal pivot, a frame supported intermediately of its length by the pivot, and a captive ball member supported on one end of and balancing the frame, whereby the ball member may be adjusted to a plurality of elevations for use with different golf clubs.

20 25 30 35 17. In apparatus of the class described, a horizontal pivot, a frame supported intermediately of its length by the pivot and a captive ball member supported on one end of and balancing the frame, whereby the ball member may be adjusted to a plurality of elevations for use with different golf clubs, and blow indicating means operable by the ball member in each selected position of elevation.
